DESIGN FOR A WALL SHOWER BRACKET

Orloff W. Holden, Chicago, Ill.

Application March 3, 1939, Serial No. 83,307

Term of patent 7 years

To all whom it may concern:

Be it known that I, Orloff W. Holden, a citizen of the United States, residing at Chicago, in the county of Cook and State of Illinois, have invented a new, original, and ornamental Design for a Wall Shower Bracket, of which the following is a specification, reference being had to the accompanying drawing, forming a part hereof.

In the drawing:

Fig. 1 is a perspective view of the wall shower bracket showing my new design;

Fig. 2 is a side elevational view of the same on a slightly reduced scale;

Fig. 3 is a top plan view of the same; and

Fig. 4 is a front elevational view of the same.

I claim:

The ornamental design for a wall shower bracket, substantially as shown.

ORLOFF W. HOLDEN.
